US0D1038852S

(12) **United States Design Patent** (10) **Patent No.:** **US D1,038,852 S**
(45) **Date of Patent:** **** Aug. 13, 2024**

(54) **WINDOW**

- (71) Applicant: **Dometic Sweden AB**, Solna (SE)
(72) Inventors: **Rickard Hederstierna**, Hägersten (SE);
                  Samuele Meda, Chichester (GB)
(73) Assignee: **Dometic Sweden AB**, Solna (SE)
(**) Term: **15 Years**
(21) Appl. No.: **29/867,842**
(22) Filed: **Nov. 10, 2022**

Related U.S. Application Data

- (62) Division of application No. 29/724,878, filed on Feb.
      20, 2020, now Pat. No. Des. 969,694.

(30) **Foreign Application Priority Data**

- Aug. 21, 2019 (EM) 006745642
(51) **LOC (14) Cl.** **12-16**
(52) **U.S. Cl.**
      USPC **D12/183**

(57) **CLAIM**

The ornamental design for a window, as shown and
described.

DESCRIPTION

FIG. 1 is a front perspective view of a window design;
FIG. 2 is a rear perspective view of the design of FIG. 1;
FIG. 3 is a front view of the design of FIG. 1;
FIG. 4 is a rear view of the design of FIG. 1;
FIG. 5 is a top view of the design of FIG. 1;
FIG. 6 is a bottom view of the design of FIG. 1;
FIG. 7 is a first side view of the design of FIG. 1, the second
side being a mirror image of the first side;
FIG. 8 is a front perspective view of a window in an alternate
position if use;
FIG. 9 is a rear perspective view of the design of FIG. 8;
FIG. 10 is a rear view of the design of FIG. 8;
FIG. 11 is a top view of the design of FIG. 8;
FIG. 12 is a bottom view of the design of FIG. 8;
FIG. 13 is a first side view of the design of FIG. 8; and,
FIG. 14 is a second side view of the design of FIG. 8.
The broken lines shown in the drawings are included for the
purpose of illustrating the unclaimed boundary and
unclaimed portions of the window. The broken lines form no
part of the claimed design.
